UNITED STATES PATENT OFFICE.

BERNHARD LANGLOTZ, OF BANGOR, MICHIGAN.

TIRE-BOLT WRENCH.

No. 923,538.

Specification of Letters Patent.

Patented June 1, 1909.

Application filed January 9, 1909. Serial No. 471,519.

To all whom it may concern:

Be it known that I, BERNHARD LANGLOTZ, a citizen of the United States of America, residing at Bangor, in the county of Van Buren and State of Michigan, have invented 5 certain new and useful Improvements in Tire-Bolt Wrenches, of which the following is a specification.

This invention relates to tire bolt wrenches 10 and has reference particularly to a device adapted to be attached to an ordinary drill press for the purpose of rotating a wrench designed to remove nuts from bolts.

An object of this invention is to provide 15 novel means applicable to drill presses now in common use whereby a nut socket is rotatably mounted in a frame, the said frame having a shaft or shank adapted to be applied to a chuck of a drill press whereby the 20 said shank is rotated, means being also provided for communicating the motion of the shank to the nut socket.

A further object of this invention is to provide a guard which may act in conjunction 25 with the nut socket for the purpose of preventing the nut socket from marring the felly to which the nut is applied.

A further object of this invention is to provide novel means for holding a bolt 30 against rotation while the nut is being removed therefrom or applied thereto, means being also provided for permitting the adjustment of the bolt holding lever in order that it may accommodate itself to rims of 35 different depths, thereby insuring that the bolt engaging projection of the lever will register with the said bolt.

With the foregoing and other objects in view, the invention consists in the details of 40 construction and in the arrangement and combination of parts to be hereinafter more fully set forth and claimed.

In describing the invention in detail, reference will be had to the accompanying 45 drawings forming part of this specification wherein like characters denote corresponding parts in the several views, in which—

Figure 1, illustrates a nut turning device applied to a drill press; and Figs. 2 and 3, 50 are detail views thereof.

In these drawings A, denotes a frame having an arm B, designed to be attached or clamped to the frame of a drill press. The frame A, is provided with two apertures C and D, the former of which is designed to receive a shank E, and the latter of which is

designed to receive a shank F' of the socket F. The shanks E and F' are connected by the gear wheels e and f, so that as the shank is driven by the drill press, the socket is rotated and as said socket is designed to be applied to a nut of a tire bolt, the said nut is turned on the bolt and is drawn therefrom. The socket F, is provided with removable filling blocks G', the said filling blocks having apertures therein of different sizes to fit correspondingly sized nuts, that is to say, the filling blocks when applied to the sockets may be made to operate on bolts of any size from one-half to one-eighth of an inch in 60 diameter, or the socket may be of a size to operate on a bolt of greater diameter, that being a detail of construction which can be varied to suit particular requirements. 65

The frame A, is provided with an extension H, having a slot I, therein in which the pivot J, of a lever K, is adjusted by means of a screw L. The lever K, is provided with a bolt engaging lug or spur M, and said lever is slotted as shown at N, to receive the shank 70 E. A spring G, is interposed between the frame A, and the lever K, and said spring normally holds the said lever elevated. The spur or lug M, is designed to engage the head of a bolt to prevent turning of the said bolt 75 when the nut is being turned on it and as the fulcrum of the lever may be changed by the screw L, the position of the spur or lug M, may be changed in order that it will engage the heads of tire bolts regardless of the depth 80 of the felly. 90

In order to prevent the socket from injuring the felly of the wheel, an apertured plate P, is supported on the frame A, by means of the arms Q, and said plate may be removed 95 owing to the fact that the said arms are removably seated in sockets in said frame.

I claim—

1. In a tire bolt wrench, a frame having an arm designed to be attached to a drill 100 press, said frame having an extension, a lever pivoted to the extension, shanks rotatable in the frame, means for gearing the shanks together, a nut socket carried by one of the shanks, a guard comprising an apertured disk having a series of arms and the said frame having sockets to receive the arms whereby the guard is held with relation to the nut socket. 105

2. In a bolt wrench, a frame, a slotted extension on the frame, a lever having a pivot in the slot, means for adjusting the pivot in 110

the slot, a shank extending from the frame and rotatable therein, said shank passing through the lever, a spring interposed between the lever and the frame and surrounding said shank, a spur on the lever, a shank rotatable in the frame and taking motion from the first mentioned shank, a nut socket on the second mentioned shank, a guard comprising an apertured disk having a series

of arms, the said frame having sockets to receive the arms whereby the guard is supported with relation to the nut socket. 10

In testimony whereof, I affix my signature in the presence of two witnesses.

BERNHARD LANGLOTZ.
